COMBINED RADIO-PHONOGRAPH AND COCKTAIL TABLE

Samuel Mallos, Ann Arbor, Mich.

Application January 19, 1956, Serial No. 39,850

Term of patent 14 years

(Cl. D33—14)

Fig. 1 is a top plan view of a combined radio-phonograph and cocktail table showing my new design;

Fig. 2 is a front elevation of the combined radio-phonograph and cocktail table;

Fig. 3 is a side elevation thereof taken in the direction of the arrows 3—3 in Fig. 2;

Fig. 4 is a rear elevational view of the combined radio-phonograph and cocktail table taken in the direction of the arrows 4—4 in Fig. 3;

Fig. 5 is a side elevation thereof taken in the direction of the arrows 5—5 in Fig. 4; and

Fig. 6 is a bottom plan view thereof as indicated by the arrows 6—6 in Fig. 4.

The dominant features of the design reside in the portions shown in full lines.

I claim:

The ornamental design for a combined radio-phonograph and cocktail table, as shown and described.
